[57] CLAIM

The ornamental design for a telescopic sight mount for rifles, as shown and described.

DESCRIPTION

FIG. 1 is a front elevational view of the telescopic sight mount for rifles showing my new design, with the rear elevational view being identical to the front; FIGS. 2 and 3 are elevational side views thereof, with the two views differing only in which end of a connecting bolt is visible;

FIG. 4 is a top view of the sight mount;
FIG. 5 is a bottom view thereof; and
FIG. 6 is a perspective view thereof.
